(57) **CLAIM**

The ornamental design for a tattoo ink bottle cap, as shown and described.

DESCRIPTION

FIG. 1 is a perspective view of a tattoo ink bottle cap in accordance with my new design;

FIG. 2 is a perspective view of the tattoo ink bottle cap as shown in FIG. 1, with the lid of the cap shown in the open position;

FIG. 3 is front view of the tattoo ink bottle cap as shown in FIG. 1;

FIG. 4 is a rear view of the tattoo ink bottle cap as shown in FIG. 1;

FIG. 5 is a first side view of the tattoo ink bottle cap shown in FIG. 1;

FIG. 6 is a second side view of the tattoo ink bottle cap shown in FIG. 1;

FIG. 7 is a top view of the tattoo ink bottle cap shown in FIG. 1;

FIG. 8 is a bottom view of the tattoo ink bottle cap shown in FIG. 1; and,

FIG. 9 is a cross-sectional view taking along line 9-9 of FIG. 7 of the tattoo ink bottle cap shown in FIG. 1.

All broken lines appearing in the drawings are for illustrative purposes and/or represent unclaimed subject matter and form no part of the claimed design.

1 Claim, 8 Drawing Sheets
